BOTTLE CARRIER

Merrill A. Grogel, Henrico County, Va., assignor to
Reynolds Metals Company, Richmond, Va., a corpora-
tion of Delaware

Filed Feb. 23, 1966, Ser. No. 1,160

Term of patent 14 years

(Cl. D58—26)

FIG.1

FIG.2

FIG. 3

FIG. 1 is a side perspective view of a bottle carrier showing my new design;

FIG. 2 is a top plan view thereof on an enlarged scale; and

FIG. 3 is an elevational view of the side opposite that of FIG. 1.

The dominant features of the design reside essentially in the full line portions of the drawing depicting an unbroken metallized panel forming the sloping sides of the carrier. The broken line showing of the bottles in FIGS. 1, 2 and 3 is for illustrative purposes only.

I claim:

The ornamental design for a bottle carrier, as shown and described.
